US00D627392S

(12) **United States Design Patent**
Graff

(10) **Patent No.:** **US D627,392 S**
(45) **Date of Patent:** **** Nov. 16, 2010**

(54) **WRITING INSTRUMENT**

(75) Inventor: **Laurence Graff**, Gstaad (CH)

(73) Assignee: **Venberg SA** (CH)

(**) Term: **14 Years**

(21) Appl. No.: **29/345,321**

(22) Filed: **Oct. 14, 2009**

(51) LOC (9) Cl. **19-06**

(52) U.S. Cl. **D19/47**

(58) Field of Classification Search .... **D19/35, D19/36, 41-51, 53-57; 24/11 F, 11 P, 11 R; 401/52, 99, 100, 104-109, 192, 195, 196**

(57) **CLAIM**

The ornamental design for a writing instrument, as shown and described.

DESCRIPTION

FIG. 1 is a perspective view of the invention;

FIG. 2 is a side view of the invention;

FIG. 3 is another side view of the invention, showing the side opposite that shown in FIG. 2;

FIG. 4 is a front view of the invention;

FIG. 5 is a back view of the invention;

FIG. 6 is a top view of the invention; and,

FIG. 7 is a bottom view of the invention.
